(57) **CLAIM**

The ornamental design for a lock plate and handle trimset assembly, as shown and described.

DESCRIPTION

FIG. 1 is a front elevational view of a lock plate and handle trimset assembly showing our new design;

FIG. 2 is a rear elevational view of the lock plate and handle trimset assembly of FIG. 1 with a knob;

FIG. 3 is a right side view of the lock plate and handle trimset assembly of FIGS. 1 and 2;

FIG. 4 is the left side being a mirror image thereof;

FIG. 5 is a top view of the lock plate and handle trimset assembly; and,

FIG. 6 is a bottom view of the lock plate and handle trimset assembly of FIG. 1.

The broken line representations are for purposes of illustration only and form no part of the claimed design.

1 Claim, 4 Drawing Sheets
